Primary Examiner — Selina Sikder(74) *Attorney, Agent, or Firm* — Birch, Stewart, Kolasch & Birch, LLP(57) **CLAIM**

The ornamental design for a smart key for automobiles, as shown and described.

DESCRIPTION

FIG. 1 is a front perspective view of a smart key for automobiles showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a rear perspective view thereof.

The broken lines depict portions of the smart key for automobiles that form no part of the claimed design.
